CLAIM

The ornamental design for a portable spray head, as shown and described.

DESCRIPTION

FIG. 1 is a top perspective view of a portable spray head according to the invention.

FIG. 2 is a bottom perspective view of the portable spray head of FIG. 1.

FIG. 3 is a first side view thereof of the portable spray head of FIG. 1.

FIG. 4 is an opposite, second side view thereof.

FIG. 5 is a front view thereof.

FIG. 6 is a rear view thereof.

FIG. 7 is a top view thereof; and,

FIG. 8 is a bottom view thereof.

The broken lines depict portions of the portable spray head that form no part of the claimed design.

1 Claim, 6 Drawing Sheets(56)
